UNITED STATES PATENT OFFICE.

RUTER W. SPRINGER, OF CARLISLE, PENNSYLVANIA.

WHISTLE.

1,403,274.

Specification of Letters Patent. Patented Jan. 10, 1922.

Application filed July 27, 1917. Serial No. 183,2004.

To all whom it may concern:

Be it known that I, RUTER W. SPRINGER, a citizen of the United States, residing at Carlisle, in the county of Cumberland and 5 State of Pennsylvania, have invented certain new and useful Improvements in Whistles, of which the following is a specification.

The object of my invention is to provide 10 an extremely portable and convenient device, upon which the bugle-signals of the U. S. Army can be given, for practical use. The tones must be loud, and shrill; and the device must be capable of standing an un- 15 limited amount of rough usage, and be capable of being held in the mouth, when not in use, without requiring the service of the hands. It should be made of metal, about six or eight inches long.

20 In the accompanying drawings, Fig. 1 is a perspective view of the device; and Fig. 2, a longitudinal section thereof.

The mouthpiece, *j*, is grooved, as shown, so that it can be held by the teeth. The 25 whistle-opening, *v*, is adjacent thereto. The tube is open, at the lower end, *h*, and has the four musical stop-openings, *z*, *y*, *x*, and *w*. These stops are to be covered, as desired, by the four fingers of the hand, preferably 30 the left hand, as indicated; and, with the opening *u*, at the lower end, *h*, of the tube, give the regular notes of the bugle-calls, do, sol, do, mi, sol,—as indicated. Assuming the 35 entire acoustic length of the tube to be 1, the stops *z*, *y*, *x*, and *w* should be at the dis-

tances $\frac{1}{3}$, $\frac{1}{2}$, $\frac{2}{3}$ and $\frac{4}{5}$ from the mouth-piece end. Since the lower "do" is very seldom used, in the bugle-calls, the little-finger need not ordinarily be employed.

This whistle can be used, for giving all the 40 usual bugle-calls, or other signals made on the same musical scale, loud enough to be heard a long distance; having no extra stops, it can be operated with only one hand, and can be quickly learned, and, being of metal 45 and all in one piece, without movable parts or reeds, it is almost impossible for it to be injured by hard usage, such as is always found in camp life. These features give it a distinct advantage over other sound-signaling devices now known or used, even over the bugle itself, for not too distant work.

What I claim, as my invention, is:

A whistle; tubular in shape; of hard material, as metal; having a mouthpiece provided with a groove in its periphery, at one end, enabling the whistle to be held by the teeth; and having an end-opening and four stop-openings, enabling it to be operated by the fingers of one hand; said openings being so located as to cause the sounding of the musical notes, do, sol, do, mi, sol, as made in the usual bugle-calls; substantially as described.

In testimony whereof I affix my signature 65 in presence of a witness.

RUTER W. SPRINGER.
